SANITARY BELT

Julian F. Fontaine, Meadville, Pa.

Application February 26, 1936, Serial No. 65,906

3 Claims. (Cl. 128—291)

The invention relates to a sanitary belt and more especially to a holder for sanitary napkins and the like.

The primary object of the invention is the provision of a belt or holder of this character, wherein in the clasps for the fastening of the modern style of gauze or knit end are incased so that there is no possibility of injury resultant from contact of the clasp with the person wearing the belt or holder and also to relieve wear on garments when the said belt or holder is worn.

Another object of the invention is the provision of a belt or holder of this character, wherein the incasing medium for each clasp is constructed from a single length of tape and carries a zipper so that it can be readily opened and closed and when closed will envelop the clasp which is of novel construction.

A further object of the invention is the provision of a belt or holder of this character, wherein in the runner of the zipper is of a construction that will act upon the attached end of the gauze or knit end of the pad, napkin or the like so as to prevent such end from interfering with the opening and closing of the zipper as such folded end will be ironed into the clasp to lie out of the way when the zipper is actuated.

A still further object of the invention is the provision of a belt or holder of this character, wherein the construction thereof is novel in its make-up and enables the attaching and detachment of a sanitary pad, napkin or the like with dispatch and ease with assurance of comfortable wear thereof.

A still further object of the invention is the provision of a belt or holder of this character, which is simple in construction, thoroughly reliable and efficient in its purpose, light in weight yet strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a perspective view of a belt or holder constructed in accordance with the invention.

Figure 2 is a fragmentary sectional view on the line 2—2 of Figure 1 looking in the direction of the arrows.

Figure 3 is a sectional view on the line 3—3 of Figure 1.

Figure 4 is a perspective view of the clasp.

Figure 5 is a fragmentary elevation showing the incasement of the clasp shown in Figure 4.

Figure 6 is an elevation of a modified form of clasp.

Figure 7 is an end view thereof.

Figure 8 is an elevation of a further modification of clasp.

Figure 9 is a fragmentary vertical longitudinal sectional view showing the clasp in Figure 8 in- 10 cased.

Similar reference characters indicate corresponding parts throughout the several views in the drawing.

Referring to the drawing in detail, A designates 15 generally a belt of elastic or other suitable strip or band material 10 having at its end portions the adjustable terminal loops 11 so that the belt is susceptible for adjustment in the fitting thereof to a wearer. These loops 11 are loosely engaged in suitable slots 12 formed in a circular head 13 of a front clasp 14 which is channeled at 15 in one side thereof and is provided with a toothed opening 16 for the detachable engagement therein of the folded end 17 of a sanitary 20 napkin or gauze covering of a sanitary pad or the like so that the latter can be fastened at the front of the belt for the wearing thereof.

Adapted for engaging the clasp 14 at the grooved or channeled portion 15 of the same is a 30 casement formed from a single length of fabric tape 18 it having major extent thereof at opposite longer edges for permanently fixing thereto the interlocking members 19 of a zipper fastener, the remaining portion of the tape 18 being permanently fastened at 20 about a reduced neck 21 of the clasp 14. Cooperating with the members 19 of the zipper fastener is the runner 22 of such fastener which serves to interlock the members 19 or separate the same and when these members are interlocked with each other the tape 18 functions as a casement for enclosing the clasp 14 to avoid contact thereof with the person in the wearing of the belt or wear of such clasp upon the wearing apparel.

The runner 22 of the zipper fastener carries a shoe 23 which has an ironing action on the folded end 17 for tucking the free terminal of this end in the channel or groove 15 of the clasp 14 on the closing of the casement to avoid interference with the members 19 in the locking and interlocking thereof under the action of the runner 22 of the zipper fastener.

The shoe 23 which is a part of the runner 22 functions to hold the end of the gauze cover- 55

ing or napkin from slipping when such end 17 is engaged in the clasp.

Hung from the rear of the belt A through the medium of a loop 24 is a rear clasp which includes the metal plate 25 formed with a channeled portion 26 and a bendable head 27, the head forming a clincher for attaching together the free longitudinal edges of the tape 28 at the inner end of the run of members 19 of the zipper fastener, the said tape 28 being the casement for the clasp. The loop 24 is stitched or otherwise made secure to the casement 28 and such rear clasp fastens the folded rear end of the sanitary napkin, pad or the like as may be worn in the use of the belt.

In Figure 6 of the drawing there is shown a modified form of clasp wherein the same in the channeled portion 30 has formed therein a longitudinally directed keyhole shaped or wedge-like slot 31 for the detachable fastening of the end of a sanitary napkin, pad or the like.

The rear clasp having the casement 28 is shown closed in Figure 5 of the drawing.

It has been found advantageous to provide in the lower free end of the clasp shown in Figures 6 and 8 of the drawing a notch 32 to receive the free terminal of the end of the gauze or napkin end 17 so as to assure further grip of this end and also to permit the runner to freely pass over such end when the casement has been completely closed by the zipper fastener on actuating the runner 22 thereof. The purpose of the shoe is to iron the end 17 for tucking and flattening thereof when engaged with the clasp and to hold this end against slipping when fastened in the clasp and the crowding of such end into the channel or groove present within the clasp.

The casement when closed maintains the end 17 in close relation to the clasp and the runner 22 of the zipper fastener assures against any slipping of the end 17 when engaged with the clasp.

In the use of the clasp at the front and rear of the belt the same can be incased when the ends of the napkin, pad or the like are attached thereto so that there is no possibility of accidental detachment of these ends in the wearing of the belt

and the napkin, pad or the like and also contact of the clasp which is made from metal or the like coming in contact with the skin of the person or damaging the wearing apparel by rubbing action thereon.

What is claimed is:

1. A belt or holder of the character described comprising a band having adjustable loop ends, a clasp suspended by the loop ends and having a channeled portion provided with an opening 10 for detachable connection of an end of a piece of material, a casement incasing said clasp and having a slide fastener for opening and closing thereof, and a runner included with said fastener and having a shoe for ironing action on the attached end of the piece of material for tucking the same in the channeled portion of said clasp.

2. A belt or holder of the character described comprising a band having adjustable loop ends, a clasp suspended by the loop ends and having a channeled portion provided with an opening 20 for detachable connection of an end of a piece of material, a casement incasing said clasp and having a slide fastener for opening and closing thereof, and a runner included with said fastener 25 and having a shoe for ironing action on the attached end of the piece of material for tucking the same in the channeled portion of said clasp, the said casement being formed from a single length of material.

3. A belt or holder of the character described comprising a band having adjustable loop ends, a clasp suspended by the loop ends and having a channeled portion provided with an opening 35 for detachable connection of an end of a piece of material, a casement incasing said clasp and having a slide fastener for opening and closing thereof, a runner included with said fastener and having a shoe for ironing action on the attached end of the piece of material for tucking 40 the same in the channeled portion of said clasp, the said casement being formed from a single length of material, and means on the clasp for the fastening of the meeting edges of said piece of material together at the inner end of the 45 zipper fastener.

JULIAN F. FONTAINE.
